CAKE PLATE

Tillie Vitto Zuckerman, Los Angeles, Calif.

Application February 11, 1955, Serial No. 34,495

Term of patent 7 years

(Cl. D44—15)

FIG. 1

I claim:

The ornamental design for a cake plate, as shown.
